UNITED STATES PATENT OFFICE.

MATTHEW F. SLATTERY AND CHARLES A. DIEHM, OF PHILADELPHIA, PENNSYLVANIA.

SAFETY-BRIDGE.

1,158,866.

Specification of Letters Patent.

Patented Nov. 2, 1915.

Application filed January 24, 1913, Serial No. 744,016. Renewed March 18, 1915. Serial No. 15,391.

To all whom it may concern:

Be it known that we, MATTHEW F. SLATTERY and CHARLES A. DIEHM, citizens of the United States, residing at Philadelphia, in 5 the county of Philadelphia and State of Pennsylvania, have invented certain new and useful Improvements in Safety-Bridges, of which the following is a specification.

This invention relates to safety bridges 10 designed for the purpose of preventing accidents to a fireman or engineer who may happen to be in the tender accompanying the locomotive at a time when the coupling between the locomotive and tender has 15 parted or become injured.

Many firemen and engineers have lost 20 their lives and become maimed through the accidental uncoupling of the locomotive from the tender. In an accident of this kind, the person in the tender is thrown forward upon the track and the momentum of the tender causes the wheels to pass over the person so thrown from the tender.

Our invention is intended to obviate this 25 character of accident and to render the lives of the engineer and fireman safe against possible accident of this character. When the coupling between the locomotive and tender has parted, owing to some defect in 30 the coupling or through some accidental cause, the air brake is uncoupled and the brakes are set, but there is a momentum to the entire train for a matter of twelve or fifteen feet, depending upon the speed at 35 which the train was going at the time the brakes were set.

Our invention comprises a device which is normally carried underneath the floor of the tender and which in case of the parting 40 of the coupling between the locomotive and tender, will be drawn outward by and be released from the locomotive to provide a strong metal net-work to prevent the person in the tender from being thrown in 45 front and under the wheels.

These and other objects may be attained by means of the construction illustrated in the accompanying drawings, in which:—

Figure 1 is a side elevation of a portion 50 of a locomotive and tender, parts being broken away to show the sliding frame members for supporting the netting; Fig. 2 is a top plan view of the tender and showing the safety device extended in position for

use after the locomotive has become detached from the tender; Fig. 3 is a front elevation of the same; Fig. 4 is a side elevation of the extended safety device and its guide, the cover of the guide being removed; Fig. 5 is a side elevation of one of the sliding members detached; Fig. 6 is a top plan view of the same.

Referring to the drawing, the numeral 1 designates the locomotive and 2 is the tender or tank which is usually coupled to 55 the locomotive and is also connected by suitable couplings to the train. The air brake train line 3 may be of the usual or any suitable type. The floor 4 of the tender is usually inclined in order that the coal or other 60 fuel resting upon the floor may be readily shoveled up by the fireman and this floor sometimes extends over the space between the locomotive and tender, as shown in Fig. 1 of the drawing. However, it will be understood that our safety device may be used 65 with any character of tender, whether there is an extension over the space of the locomotive or not.

Connected to the opposite sides of the 70 tender near the front thereof, is a guide casing 5 provided with a curved guideway 6 extending longitudinally thereof and provided with shoulders 7 and 8. Anti-friction rollers 9 and 10 are journaled at opposite 75 sides of the guideway 6 as shown more clearly in Fig. 1. Mounted to slide longitudinally in the guideways 6 are side supporting members 11 for the netting 12^a. The members 11 may each be in the form of 80 a curved rod or bar and at one end each member is provided with a down turned lug 12 having an anti-friction roller 13. The rings 14 on the sides of the netting 12^a surround the members 11 and slide thereon, so 85 that when the members 11 are pushed back into the casing, the netting 12^a will fold and be disposed within a box or casing 15, entirely protected from the weather and out of 90 the way. It is to be noted that the rings 14 are permanently connected to the members 11 to keep the netting always extended 95 laterally.

At the front end of the netting rings 16 are provided and these rings surround a 100 rod 17 adjustably mounted in the members 11 and provided with lock nuts 18 for permitting the members 11 to be adjusted trans-

versely in order to provide means whereby the safety device may be fitted to tenders of different widths.

Pivottally mounted on the front end of the members 11 are gravity hooks 19 and these hooks are normally connected by means of a chain 20 to a ring or staple 21 on the locomotive, said chain having a certain amount of slack, as shown in Fig. 1.

10 Connected to the inner sides of the members 11 are sliding latch rods 22 mounted to move in rings or suitable keepers 23, said rods being each provided with a ring 24 at the front end adapted to engage the bill 25 of the hook 19 to hold it in proper engagement with the member 11 and with the chain 20.

At the rear end of the latch 22 is a down turned stop 26 and interposed between said stop and the lug 12 is a cushion spring 27, the purpose of which is to always insure the engagement of the ring 24 with the bill 25 of the hook 19 and also to serve the purpose of a cushion in case of a jar between the 25 front ends of the members 11 and the locomotive or other part. Within the guideway 6 is a pivoted back stop 28, said stop being pivoted at 29 and provided on its free end with an extended finger 30 which projects through a slot in the casing 5 so that the stop may be thrown up into its recess against the shoulders 7 when the netting is to be collapsed or folded within the box or casing 14.

35 A spring 31 is secured to the upper wall of each side of the guideway 6 and the purpose of these springs is to hold the members 11 down in place. A curved guide slot 32 is provided in the casing 5 to give room for 40 the sliding latch 22.

The operation of our invention may be briefly described as follows: When the coupling between the locomotive and tender has parted and the train line 3 has separated, 45 there is a pull upon the chain 20 connected to the hooks 19 and when the pull is sufficient, the bills 25 of the hooks are disengaged from the rings 24 on the latch 22 and swung out into the position shown in Fig. 4, 50 thus releasing the chain 20 from the hooks after the supporting members 11 have been withdrawn to the position shown in Fig. 4. When in this position, it will be noted that

the back stop 28 drops into the position shown in said figure and that the spring 27 55 is compressed. In this condition, should the fireman or other person in the tender at the time of separation of the locomotive therefrom be thrown forward by the jar or momentum of the tender, he would land in the 60 net 12^a and be prevented from dropping out out onto the track in front of the moving tender.

From the foregoing, it will be obvious that our invention is simple in construction, 65 reliable and efficient in operation, can be readily attached to any tender, is entirely out of the way when not required for use and is automatic in its extension to position for use in case of accident.

We claim:—

1. A safety bridge comprising guideways connected to the opposite sides of a locomotive tender and provided with curved guide grooves, slidable members mounted in said grooves and provided with rollers, each of said slidable members being provided with a gravity hook at its front end, chains adapted to be connected to the locomotive and to said hooks, a slidable latch rod for holding each of the hooks closed, a buffer spring at the rear end of each of said latch rods, a spring for holding said members in proper position, and a netting connected to said slidable members.

2. A safety bridge comprising guideways at the sides of a locomotive tender, supporting members mounted to slide in grooves in said guides, rollers mounted in said guides on said members, a slidable latch connected to each of said members and provided with a ring, a gravity hook at the front end of each of said members, a spring at the rear end of each of said latches, a back stop on each of said guides, and a netting connected 90 to said slidable members and adapted to be extended when said members are drawn outward.

In testimony whereof we have affixed our signatures in presence of two witnesses.

MATTHEW F. SLATTERY.
CHARLES A. DIEHM.
